UNITED STATES PATENT OFFICE.

SAMUEL A. BULLOCK, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

SINGLE-TRUCK SPRING-STABILIZER.

1,231,487.

Specification of Letters Patent. Patented June 26, 1917.

Application filed May 3, 1916. Serial No. 95,098.

To all whom it may concern:

Be it known that I, SAMUEL A. BULLOCK, a citizen of the United States, residing in Philadelphia, Pennsylvania, have invented 5 certain Improvements in Single-Truck Spring-Stabilizers, of which the following is a specification.

My invention relates to improvements in stabilizing cars which are supported on a 10 single truck structure, particularly those which are driven from motors carried by the truck structure.

While the invention is especially adapted 15 for use in connection with cars which are driven as single units, my invention can be used in connection with cars which are coupled together to form a train.

The object of my invention is to provide 20 means for stabilizing a car so as to reduce the "nosing" to such an extent that the car will travel more evenly than heretofore.

By this invention the synchronism of the 25 end swing of the car body is broken up and a more pleasant lateral motion is produced which is opposed to the so called objectionable nosing.

In the accompanying drawings:

Figure 1 is a side view of a car, showing 30 the body portion in outline and illustrating my invention;

Fig. 2 is a sectional view showing the spring suspension at one end of the car;

Fig. 3 is a sectional view showing the 35 spring suspension at the opposite end of the car;

Fig. 4 is a view of a spring cap which I prefer to use; and

Fig. 5 is a plan view of the spring cap.

Referring to the drawings, 1 is the body 40 of the car. 2, 2 are the pedestal frames which are rigidly secured to the car body in any suitable manner. 3, 3 are the boxes for the axles 4, 4^a. 5 is a beam supported by the boxes 3 and carrying certain mechanism of 45 the truck to which this invention does not relate. This construction is duplicated on the opposite side of the car.

6, 6 are the wheels mounted on the axles 4, 4^a, in the ordinary manner. Supported on 50 the boxes are the springs 7, 7^a, each having a center strap 17 located in a recess in each box, and hung from the ends of the springs

7 are rods 8 carrying at their lower ends the 55 spring caps 9 on which are mounted the coiled springs 10, each carrying a spring

plate 11 which, in turn, carries a coiled spring 12 on which is mounted a cap 13 bearing against the under side of the extension of the pedestal frame 2, which is attached to the car body. The rods 8 extend 60 entirely through the caps 9 and 13 and the spring plate 11, and have at their lower ends nuts 14 which bear against a convexed bearing 15 on the cap plate 9, so that the entire structure which forms one of the stabilizers 65 can swing from the bearing 15, which forms the fulcrum.

It will be noticed that the coils of the 70 springs 12 are of smaller outside diameter than those of the springs 10, thus producing a shock absorbing device. The two spring structures 16, at each side of the axles 4, 75 form one section of a stabilizer. At the opposite end of the car is a duplicate of the construction just described, but the parts of the stabilizers 16^a on each side of the axle 4^a are so arranged that the fulcrum 15^a is closer to the ends of the springs 7^a than those of the elements 16. Each stabilizing 80 section 16^a consists of the rod 8^a, cap plate 9^a, springs 10^a and 12^a, cap plate 13^a, and spring plate 11^a.

It will be noticed, upon referring particularly to Figs. 4 and 5, that the cap plates 9 and 9^a are identical, only when the cap 85 plate is used as indicated at 9^a it is inverted and the nut 14^a is located within the cap plate, resting against the curved bearing formed, as clearly shown in Fig. 4. By this construction, all of the springs 10 and 10^a 90 are of the same size and length, and all of the springs 12 and 12^a are of the same size and length. But the length of the rod 8 between its fulcrum and the spring 7 is 95 greater than the length of the rod 8^a between its fulcrum and its spring 7^a.

I have found that where all of the rods 100 are of the same length and there is any unevenness in the track, the body of the car will "nose" considerably, due to the synchronism of the swing of the car body, but by making the fulcrum of the rods of the spring stabilizer at one end of the car body of a different length from those at the other end of the body, the synchronism is broken 105 and an exceedingly pleasant floating action is produced.

I claim:

1. The combination in a car body, of a body portion; a single truck under the body 110

portion and having two pedestal structures at each end of the car; boxes mounted in the pedestals; axles located in the boxes; semi-elliptic springs mounted on the boxes; and a 5 spring stabilizer suspended from the end of each spring, the upper portion of each stabilizer bearing against the pedestal, the spring stabilizer at one end of the car being of a different length than that at the opposite 10 end of the car.

2. The combination in a car, of a body portion; pedestals secured to the body portion; axles mounted in the pedestals; semi-elliptic springs mounted on the axles; 15 spring stabilizers at the ends of the semi-elliptic springs, adapted to act as both stabilizers and shock absorbers; the stabilizers at one end of the car truck being of a greater length than those at the opposite end 20 of the car so that the swing of the car body on the axles at one end will be different from that at the opposite end.

3. The combination in a car, of a body portion; pedestals secured to the body portion at each end thereof; boxes mounted on 25 the pedestals; axles adapted to the boxes;

a semi-elliptic spring mounted in each box; a rod hung from the end of each spring; a nut on the end of the rod; a cap plate supported by the nut; two springs of different 30 diameters and different thicknesses supported one above the other by the cap plate; a cap plate at the upper end bearing against the pedestal, the fulcrums of the spring structures at the ends of the car being so 35 arranged as to give a greater leverage at one end than at the other.

4. A cap plate for the spring suspension of a car, said cap plate having a deep dished portion perforated for the passage of a suspension rod and having an external flange at the opposite end for supporting the 40 spring, the said cap plate being reversible.

5. A cap plate for a spring suspension of a car having a deep dished portion perforated at the bottom and having an external flange at the upper side for supporting a coiled spring, the cap having a convexed 45 bearing surface on each side at the opening, forming a bearing for a nut or head of a 50 rod extending through the cap plate.

SAMUEL A. BULLOCK.
